Primary Examiner — T Chase Nelson*Assistant Examiner* — Ania Aman(74) *Attorney, Agent, or Firm* — Abelman, Frayne & Schwab(57) **CLAIM**

The ornamental design for a heater, as shown and described.

DESCRIPTION

FIG. 1 is a top, front, right side perspective view of a heater showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines showing structural features are included for the purpose of illustrating non-claimed subject matter and form no part of the claimed design.
